UNITED STATES PATENT OFFICE.

WALTER MYERS, OF BRIDGEPORT, CONNECTICUT, ASSIGNOR TO THE SINGER MANUFACTURING COMPANY, A CORPORATION OF NEW JERSEY.

ORNAMENTAL-STITCH SEWING-MACHINE.

1,267,581.

Specification of Letters Patent.

Patented May 28, 1918.

Application filed October 8, 1914. Serial No. 865,769.

To all whom it may concern:

Be it known that I, WALTER MYERS, a citizen of the United States, residing at Bridgeport, in the county of Fairfield and State of Connecticut, have invented certain new and useful Improvements in Ornamental-Stitch Sewing-Machines, of which the following is a specification, reference being had therein to the accompanying drawings.

10 This invention relates to improvements in ornamental stitch sewing machines and has for its object to effect a predetermined design or figure, and to this end the usual cloth-presser-carrying-bar is provided with 15 a frame into which is journaled a rotary pattern-cam having a cam-groove of a character to effect a given design, said groove being tracked by a stationary follower and the needle-carrying-bar controlled to effect 20 varieties of the given design without an interchange of pattern-cams.

In the accompanying drawings, which form a part of the specification, Figures 1, 2 and 3 are views in front side elevation, 25 plan and rear side elevation respectively, of one form of ornamental stitch sewing machine equipped with the present invention. Fig. 4 a perspective of the cloth-presser or attachment for presenting the 30 fabric being acted on to the action of the stitch-forming mechanism. Fig. 5 a cross section on the line A—A, Fig. 4. Figs. 6, 7 and 8, a sectional view of the needle vibrating mechanism including the switch-cam carried by the main-shaft; a perspective of 35 the needle vibrating segment-lever and a like view of the needle vibrating segment-lever-carrier, respectively, the latter view including the switch-cam follower. Fig. 9, a 40 plan of the front end portion of the cloth-plate, together with the needle-plate. Fig. 10, details in perspective of one form of pattern-cam. Fig. 11, a second form of pattern-cam. Fig. 12, diagrammatic views of 45 the designs effected by the pattern-cam of Fig. 10, the smaller view representing the largest design effected by said cam. Fig. 13, diagrammatic views of the design effected by the pattern-cam of Fig. 11, the smaller 50 view representing the largest design effected by said cam.

The present invention is shown as applied to a Singer ornamental stitch sewing machine, the same as is represented by United

States patent application Serial No. 829,798, 55 filed April 6, 1914.

Referring to the figures, 1 represents the bed-plate of the sewing machine upon which is mounted the bracket-arm comprising the standard 2 and arm bracket 3, 4 the main- 60 or needle-bar driving shaft provided at its rear end with the hand- or band-wheel 5 and at its opposite end with the take-up cam 6, 7 the sewing needle, 8 the needle-carrying-bar operatively connected by the link 9 with 65 said take-up cam, the needle-carrying-bar 8 being mounted in suitable bearings formed in the swinging gate 10 journaled on pintle screws, as 11, in a manner common to earlier constructions, 12 the take-up lever, 13 70 thread-tension and 14 the thread-controller.

15 represents the lower or looper actuating shaft operatively connected at its rear end by suitable quartering cranks, as 16, with the main-shaft 4, its opposite end being 75 provided with a flange 17 connected by link 18 with the crank 19 carried by the gear-shaft 20 provided with the gear-member 21 operatively connected with a like gear-member 22 carried by the loop-taker driver 23, 80 thus transmitting stitch-forming movements to the loop-taker 24, as in earlier constructions.

25 represents one form of commonly employed switch-cam into which tracks a fol- 85 lower 26 journaled in a suitable bearing 27 preferably formed integral with the segment lever carrier 28, which latter is provided with a hollow shaft 29 journaled in a suitable bearing 30 formed in the bracket- 90 arm, the rear end of said shaft being provided with a suitably secured collar 31 to hold said shaft against accidental endwise movement. 32 denotes a segment lever pro- 95 vided with a hollow shaft 33 journaled in the hollow shaft 29, a segmental guide-slot 34, arcuate slot 35, notch 36 and spring- 100 controlled plunger 37 provided with a seat 38 which registers with one or the other of the openings 39 or 40 formed in the seg- 105 ment lever carrier 28, dependent upon the character of the seam or figure desired.

Into the hollow shaft 33 is slidably mounted a plunger 41 provided at one end with an enlarged oval head 42, its opposite end being 105 threaded to receive the screw 43 whose slotted head 44 is arranged on the side of the dividing wall 45, formed integral with the

shaft 33, opposite to that of its threaded end, thus permitting endwise movements of said plunger of substantially the length of the body portion of said screw, a spring 46 confined between said slotted head and the screw 47, acting to hold the plunger 41 in its outward position as shown in Figs. 2 and 6. 49 denotes a sleeve secured by screw 50 to the rear end of the hollow shaft 33, and between the enlarged portion 51 of said sleeve and the collar 31 carried by the shaft 29 is confined the spring 52 which normally acts to hold the segment lever 32 in operative relation with its carrier 28, for a purpose later to be explained.

15 53 represents a bracket secured by screws, as 54, to the bracket-arm, 55 a rock-shaft journalized in suitable bearings formed in said bracket and onto said shaft is mounted to move endwise a yoke 56 provided with a crank-arm 57 carrying a cam-plate 58, said yoke being secured to turn with said shaft by a teated screw 59 threaded into said yoke and entering a suitable slot (not shown) formed into said shaft, a cam lever 60 pivoted on a suitable pin (not shown), passing through said shaft, acting in opposition to the resiliency of the spring 61 to move said yoke toward the rear side of the machine, thus carrying said cam-plate out of effective relationship with the head 42 of the plunger 41, for a purpose later to be explained.

35 62 represents an oscillating shaft crank suitably secured upon the shaft 55 and at its free end provided with a stud-screw 63 which tracks a slot 64 formed in the segment lever slide connection 65, the lower end of the latter being provided with a suitable opening (not shown) through which extends a stud 66 threaded into the slide block 67 tracking the segmental guide-slot 34, said stud also acting as the pivotal connection for one end of the swinging gate connection 68, the opposite end of the latter being pivotally connected to the swinging gate 10 by a suitable ball joint connection 69.

50 70 represents a segmental slide block stop 50 adjustably secured in the guide-slot 34, the wing nut 71, threaded onto the stud 66, acting to secure the slide block 67 in given adjustment when it is desired to effect successive zigzag stitches of a given amplitude of needle vibration, a spring 72 attached at one end to the shaft crank 62 and at its opposite end to the connection 65 acting to normally hold the stud 63 at the lower end of the slot 64.

60 73 represents a thread tension releasing crank-arm suitably secured to the rock-shaft 55, said crank-arm, together with the shaft crank 62, acting to secure said shaft against accidental endwise movement, the 65 crank arm being provided with a depending

arm lug 74 which, when depressed, acts on the end of the tension stud 75 to move the latter in opposition to the resiliency of the flat spring 76 and coiled spring 77, thus lessening the degree of tension exerted by 70 said latter spring on the tension disks, as 78.

To the front end of the crank-arm 73 is pivotally attached one end of a link 79 whose opposite end is pivotally attached to a rock-lever 80 journaled on a stud 81 threaded 75 into the arm bracket, and to the opposite end of said rock-lever is pivotally attached, by stud-screw 82, a hub 83 into which is threaded the upper end of a treadle-actuated rod 84 which, in practice, is operatively connected with a suitable treadle (not shown), a spring 85 acting to normally hold, through the connections previously pointed out, the axis of the stud 66 in alinement with the axis of the hollow shaft 33.

85 86 represents a spring depressed hollow cloth-presser carrying bar into which is mounted a rod 87 threaded at its upper end to receive the nut 88 and at its opposite end threaded into an enlarged extension 89 provided with oppositely arranged walls, as 90, and gripping jaws, as 91, which latter are arranged slightly below the lower end of said cloth-presser carrying bar, 92 denotes the cloth-presser bracket provided with the slot 93, the latter, in practice, embracing the walls 90, the nut 88 acting to raise the rod 87 and grip the oppositely arranged surfaces adjacent to said slots between the lower end of the cloth-presser-carrying-bar 100 and the gripping jaws 91, thus securing the cloth-presser bracket to the lower end of the cloth-presser-carrying-bar.

When it is desired to stitch a figure of uniform stitches, the operator adjusts and 105 by wing nut 71 secures the slide 67 to effect the desired amplitude of vibration of the needle, and during the stitching operation the fabric is manually turned under the needle for one, two or more rotations dependent upon the desired character of product, and at the completion of the formation of the stitches the operator moves the cam-lever 60 to its vertical position, thus permitting the spring 61 to move the cam-plate 115 58 in line with the head 42 of the plunger 41, when the operator, through the manipulation of a suitable treadle, rocks the shaft 55 which causes the cam-plate 58 to move the plunger 41, and through the medium of spring 46 and nut 47, move the segment lever toward the operator a distance sufficient to release the teat 38 from engagement with the opening 40 and with the stationary lug 94 in engagement with the notch 120 36 formed in said segment lever, thus holding the latter out of engagement with the segment lever carrier and with the needle in its outside or depth stitch position or in 125 position to form stitches about the figure in 130

line with the depth stitches, after which the operator returns the lever 60 to its former position, it being understood that radial stitches of varying lengths may be employed through the manipulation of a suitable treadle connected, as previously described, with the rock-shaft 55, it being understood that the spring 46 when depressed is of sufficient strength to overcome the strength of the spring 52.

The cloth-presser or embroidering attachment, best represented by Figs. 4, 5, 10 and 11, is secured by screws, as 95 to the cloth-presser bracket 92 and comprises a cam-follower bracket 96 provided with a bracket-arm 97 into the free end of which is suitably secured a pin 98 provided with a cam-follower 99, the opposite ends of the bracket 96 being provided with bearing lugs, as 100, into which is journaled the upright frame-shaft 102 of the cloth-presser-frame 103, a screw 104 acting to secure said bearing shaft against accidental movement in the direction of its length.

105 represents the pattern-cam disk for effecting the designs illustrated in Fig. 12, said cam-disk being provided with an opening 106, cam-groove 107, bearing flange 108, depressed portion 109 into which the opening 106 is formed, the walls, as 110, of said opening depending below the under surface of the depressed portion 109 in the form of a thin rib, as 111, the free edges of which bear directly upon the fabric being acted on when effecting the stitching operation.

Referring more particularly to Figs. 5 and 10, the bearing flange 108 of the disk 105 is, by the employment of suitable ball bearings as 112, journaled in the opening 113 in the frame 103, the flange 114 of said disk being threaded into the wall 115 of the retaining disk 116 and to the latter is secured by suitable screws, as 117 threaded into suitable openings as 118, the fabric feeding member 119 provided with spring yielding fabric engaging members 120, thus effecting the attachment shown complete in Fig. 4. 121 denotes a second pattern-cam disk interchangeable with the cam-disk 105 for effecting the designs represented by Fig. 13.

The sequence of the relative movements of the stitch-forming mechanism and cloth-presser for effecting the designs represented by Fig. 12 are as follows:—Supposing the cloth-presser, best represented by Fig. 4, to be positioned with respect to the stitch-forming mechanism as shown in Figs. 1 and 3, the operator places the fabric upon the cloth-plate 122 provided with the needle-plate 123 and under the fabric engaging elements 120, when the slide-block 67, secured by nut 71 or held through a manually controlled treadle operatively connected with said block, positioned in the guide-slot

34 to effect the desired amplitude of lateral movement of the needle-bar which, for the purpose of the present consideration, corresponds to the length of overseam stitch represented by view *a* of Fig. 12, when the cam 105, together with the material, is manually rotated for a single stitching operation; but if it is desired to add to the four sides the zigzag edge stitches 124 of the enlarged view *b* of Fig. 12, the operator permits the spring 85 to move the slide-block 67 toward the axis of the hollow shaft 33 a distance sufficient to effect the desired amplitude of needle vibration, but if it is desired to finish the edge by a straight line of stitches as shown by the edges 125 the operator permits the spring 85 to move the slide-block until the axis of the nut 71 and the hollow shaft 33 coincide, the fabric and cam-disk 105 being given one rotation for each operation.

As the cam-follower is stationary and the cam-groove eccentric or irregularly formed with respect to the axis of the cam-disk, the latter is given lateral movements in directions corresponding to the dotted lines 90 A—A, Fig. 4.

The cam represented by Fig. 11 is interchangeable with the cam 105 and effects view *a* of Fig. 13, together with the varieties represented by the enlarged views *b* and *c* 95 and in the same manner as view *a* of Fig. 12.

From the foregoing it is to be understood that the present invention is directed to the providing of a cloth-presser which effects given designs or figures without any care on 100 the part of the operator except to give to the cam-disk its step-by-step rotary feed movements, and the stitching of certain varieties of a given design by changes in amplitude of needle vibration.

Having thus set forth the nature of the invention, what I claim herein is:—

1. In a machine for ornamental stitching, the combination with a rotary pattern-cam disk, a stitch-forming mechanism including 110 a cloth-presser carrying bar and a needle having lateral movements, of a cloth-presser carried by said bar and on which said disk is mounted and means, including a cam-follower operatively connected with said disk, 115 for giving to said cloth-presser lateral movements.

2. In a machine for ornamental stitching, the combination with a rotary pattern-cam disk, a stitch-forming mechanism including 120 a cloth-presser carrying bar and a needle having lateral movements and means for varying the amplitude of the latter, of a cloth-presser carried by said bar and upon which is mounted said disk, and means including a cam-follower held against movement in the direction of the diameter of said disk for giving to said cloth-presser lateral movements.

3. In a machine for ornamental stitching, 130

- 4
- the combination with a rotary pattern-cam disk of given design, a stitch-forming mechanism including a cloth-presser carrying-bar and a needle having lateral movements and 5 means for varying their amplitude, of a cloth-presser on which is mounted said disk and means including a cam-follower operatively connected with said disk for giving to said presser-foot lateral movements, the 10 changes in amplitude of the lateral movements of said needle controlled to effect changes in the relative arrangement of the individual stitches forming the figure controlled by said disk.
- 15 4. In a machine for ornamental stitching, the combination with a rotary pattern-cam disk carrying a fabric feeding member, a stitch-forming mechanism including a cloth-presser carrying bar and a needle having lateral movements, of a cloth-presser carried by 20 said bar and upon which is mounted said disk, and means including a cam-follower operatively connected with said disk for

giving to said cloth-presser lateral movements. 25

5. In a sewing machine for ornamental stitching, the combination with a pattern-cam disk carrying a fabric feeding element, a stitch-forming mechanism including a cloth-presser carrying bar and a needle having lateral movements, of a cloth-presser mechanism comprising a resiliently depressed cloth-presser carrying bar provided with a cloth-presser frame into which is journaled said disk and means, including a cam-follower held against movement in the direction of the diameter of said disk, for giving to said frame lateral movements. 30

In testimony whereof, I have signed my name to this specification, in the presence of 40 two subscribing witnesses.

WALTER MYERS.
